2 Sheets-Sheet 2

UNITED STATES PATENT OFFICE.

DANIEL A. DORAN, OF YONKERS, NEW YORK.

MAIL ELEVATOR.

Application filed May 26, 1920. Serial No. 384,398.

To all whom it may concern:

Be it known that I, DANIEL A. DORAN, a citizen of the United States, and residing at Yonkers, in the county of Westchester and State of New York, have invented certain new and useful Improvements in Mail Elevators, of which the following is a specification, such as will enable those skilled in the art to which it appertains to make and use the same.

This invention relates to apparatus for raising and lowering mail in an apartment house or other building or dwelling, and the object of the invention is to provide an improved apparatus of the class specified employing one or more mail boxes and a corresponding number of tubular shafts or runways through which said mail boxes are adapted to pass from a predetermined point on the ground floor of a building to a predetermined floor of such building; a further object being to provide an improved tubular shaft or runway which is so constructed as to permit of the passage of a mail box therethrough around corners or angles and curvatures formed in said tubular shaft; a further object of the invention being to provide an improved means for raising and lowering a mail box in a tubular shaft; a still further object being to provide means for automatically stopping the mail box or the means for operating the same when the mail box reaches its extreme lowest and highest position; and with these and other objects in view the invention consists in an apparatus of the class and for the purpose specified which is simple in construction and operation and efficient in use, and which is constructed and operated as hereinafter described and claimed.

The invention described and claimed herein is an improvement on that described and claimed in a prior application filed by me Sept. 29, 1919, Serial No. 327,169, and is fully disclosed in the following specification, of which the accompanying drawing forms a part, in which the separate parts of my improvement are designated by suitable reference characters in each of the views, and in which:—

Fig. 1 is a diagrammatic view illustrating one use of my improved apparatus with

parts of the construction broken away and in section;

Fig. 2 a sectional detail view on the line 2—2 of Fig. 1;

Fig. 3 a diagrammatic view of the electric circuit employed;

Fig. 4 a view similar to Fig. 1 but showing only a part of the construction on an enlarged scale and with certain other details of construction not shown in Fig. 1;

Fig. 5 a partial section on the line 5—5 of Fig. 4;

Fig. 6 a partial section on the line 6—6 of Fig. 5;

Fig. 7 a detail view of one of the mail boxes which I employ and which is shown in section in Fig. 5; and,

Fig. 8 a transverse sectional view of the tubular shaft or runway which I employ and indicating a plan view of a mail box and its relative position in said shaft.

In Figs. 1 and 5 of the drawing I have shown at 10 a casing or framework which is preferably mounted at a predetermined point on the ground floor of a building, and which in the construction shown is subdivided into three sections 11, 12 and 13 on the top of which are mounted tubular shafts or runways 14, 15 and 16. The separate compartments 11, 12 and 13 are provided on the outer face thereof and adjacent to the top portion thereof with elongated apertures 17 through which mail may be passed into mail boxes 18 which are normally mounted within the compartments 11, 12 and 13 as indicated in dotted lines in Fig. 1 and shown in full lines in Fig. 5.

The tubular shafts or runways are adapted to pass upwardly through the building and said shafts terminate on the separate floors or floor levels of the building. It has also been found that it is necessary on some occasions to locate the top portions of the shafts or runways at points rearward or forward of and above the compartments 11, 12 and 13 and in order to provide for such cases, it is necessary to form angular or elbow portions as shown at 19 in Fig. 1 in the shaft or runway, or to provide curved and twisted portions therein as is shown at 20 in said figure in the operation of passing around a corner, or to form gradual curved and offset portions as shown at 21 in said

figure. The angular or elbow-shaped portions 19 are joined by an inclined portion 22 in order to facilitate the movement of the mail box in shafts or runways so formed. 5 It will be apparent that the shafts or runways may be mounted in, or imbedded in the walls of the building in the construction thereof, or may be mounted in the building in any desired manner, and the compartments or chambers in which the tubular shafts or runways are mounted, are provided adjacent to the upper end portions of said shafts or runways with door openings 23 adapted to be closed by doors 24, and one 15 of said door openings and doors is indicated in Figs. 5 and 6 of the drawing.

In the accompanying drawing, I have shown only one of the tubular shafts or runways complete, namely, the shaft or runway 20 15, and mounted on the top portion of said shaft is a frame member 25 having a shaft 26 which passes longitudinally therethrough and to the central portion of which is secured a gear 27 which meshes with a gear 25 28 on the shaft 29 of a motor 30 mounted in connection with the frame member 25. Mounted on the shaft 26 at the opposite sides of the gear 27 are springs 31 and 32, one end of each of which is secured to the 30 shaft as shown at 33 and the other ends of which are secured to spools 34 and 35 as shown at 36, which spools are adapted to be rotated by said shaft 26 through the springs 31 and 32 respectively.

35 Mounted on the spool 34 is a cable 37, the free end portion of which passes downwardly through the shaft 15 and is secured to the bottom of the mail box 18 within the compartment 12, as indicated at 38 and this 40 cable passes around a guide pulley 39 at the top portion of the shaft 15 and around a similar pulley 40 within the compartment 12, as indicated in dotted lines in Fig. 1 and shown in full lines in Fig. 5. The cable 37 45 also passes through eyes 41 at one side of the mail box 18, and this serves to guide the cable in the movement of the mail box through the shaft 15.

50 Mounted on the spool 35 is a cable 42 which is adapted to pass through the shaft 15 and is secured to the top of the mail box 18 as shown at 43, and said cable passes around a guide pulley 44 at the top of the shaft 15. From the foregoing it will be seen 55 that in the upward movement of the mail box in the shaft 15, the cable 37 is unwound from the spool 34 and the cable 42 wound upon the spool 35, and in the downward movement of said mail box, the cable 37 is 60 rewound upon the spool 34 and the cable 42 unwound from the spool 35, and by reason of the connection of the spools 34 and 35 with the drive shaft 26 any slack produced in the cables or any tension thereon will be 65 taken up by said springs, the springs being

wound in opposite directions to constantly keep the mail box under tension and to prevent free movement thereof in the shaft 15.

Mounted in the upper end portion of the shaft 15 is a transverse rod 45 upon which 70 is mounted two levers 46 and 47 free to oscillate thereon, one end portion of said levers being forked as shown at 48 to engage the separate cables 37 and 42, and the other ends of said levers being provided with 75 contact disks 49 and 50 respectively.

Mounted in connection with the top portion of the shaft 15 in juxtaposition to the levers 46 and 47 is an insulated plate 51 having two contact members 52 and 53 in connection with which the contact disks 49 and 50 are adapted to operate and another contact member 54 is mounted on the plate 51, or an extension 55 of said plate. The door 24 which is located adjacent to the top portion of the shaft 15 is provided at the top portion thereof with an inwardly directed arc-shaped segment 56 to which is secured two contact strips 57 and 58, the strip 58 being longer than the strip 57 as clearly illustrated in Fig. 3. The contact strips 57 and 58 are adapted to operate in connection with the contact member 54, as hereinafter described, and the levers 46 and 47, or the contact disks 49 and 50 thereof, are normally held in engagement with the contact members 52 and 53 by springs 59.

The mail boxes 18 are preferably box-shaped in form, or are composed of side walls 60 jointed by top and bottom members 100 61 and 62 and the front and back portions of the boxes are open. Mounted in the front and back portions of the mail boxes are transverse retaining rods 63, the central portions of which are bent downwardly to form 105 arc-shaped members 64 which are also bent inwardly to a slight extent as shown in Fig. 5 of the drawing, and the object of the arc-shaped members 64 on the rods 63 is to prevent the accidental displacement of the mail 110 within the box 18 and yet facilitate the operation of removing such mail therefrom. The angular arrangement of the members 64 will also prevent the passage of mail outwardly through the boxes in the operation of 115 inserting mail thereinto through the aperture 17 in the compartment 12, as will be clearly evident on a consideration of Fig. 5 of the drawing.

In the operation of the apparatus, the 120 shaft 26 is rotated by the motor 30 in opposite directions in order to unwind and rewind the cables 37 and 42 on the separate spools 34 and 35, and in Fig. 3 of the drawing, I have indicated an electric circuit for 125 accomplishing the desired result, and in said figure I have shown at 65 and 66 two main circuit wires from any suitable source of electrical supply, the wire 65 being connected with the motor 30 while the wire 66 130

is connected with the contact member 54. A wire 67 is connected with the contact member 52 and the contact plate 57. Another circuit wire 68 is connected with the contact member 53 and the contact plate 58, and two other circuit wires 69 and 70 are connected with the contact disks 49 and 50 respectively, and with the motor 30. The passage of the current into the motor 30 through one of the wires 69-70 will cause said motor to operate in opposite directions. It will be apparent on a consideration of Fig. 3 that the direction of the current or its passage to the motor 30 through the wires 69 and 70 is controlled through the contact plates 57 and 58, the contact members 52 and 53 and the contact disks 49 and 50.

In the normal position of the various parts of my improved apparatus and referring to the shaft 15 which is shown complete in the accompanying drawing, the mail box 18 of said shaft is in its lowest position and a knob or sleeve 71 on the cable 37 is in engagement with the lever 46 and is holding such lever in its inoperative position against the action of the spring 59, or with the contact disk 49 of said lever out of engagement with the contact member 52. The lever 47 is held in operative position by the spring 59 to close the circuit through the contact disk 50 and contact member 53. The circuit through the contact member 54 and contact plate 57 is also closed by reason of the fact that the door 24 is in its closed position.

With the parts in the above described position, if the door 24 be opened the contact plate 57 will be moved out of engagement with the contact member 54 and the contact plate 58 brought into engagement with said member thus closing the circuit to the motor 30 through said contacts, the contact disk 50 and member 53 and through the wire 70, and the operation of the motor will raise the mail box 18 in the shaft 15, as will be apparent. In the above operation the cable 37 is unwound from the spool 34 and the cable 42 is wound upon the spool 35.

When the mail box 18 is about to reach the limit of its upward movement a knob or sleeve 72 on the cable 42 just above the mail box 18 operates in connection with the lever 47 to break the circuit to the motor 30 from the contact disk 50 and contact member 53 thus stopping the upward movement of the mail box in which position of said mail box the same is in juxtaposition to the door 24 and a discharge aperture 73 in the shaft 15, which aperture is indicated in Fig. 1 of the drawing.

It will be understood that in the upward movement of the mail box, as above described, the circuit through the contact disk 49 and contact member 52 will be closed by reason of the downward movement of the knob 71, and in the operation of closing the

door 24 the circuit will again be completed through the contact member 54 and disk 57 thus completing the circuit to the motor 30 through the wire 69, and the above operation of the spools will be reversed and the mail box 18 will be moved downwardly. The downward movement of said mail box will be stopped by the engagement of the knob or sleeve 71 with the lever 46 to break the circuit through the contact disk 49 and contact member 52 thus returning the various parts of the apparatus to their normal position.

It will be understood that each of the other shafts 14 and 16 will be provided at the top thereof with the frame member 25 and the various parts connected therewith as is shown in connection with the shaft 15 and the mail boxes in the compartments 11 and 13 will be automatically raised and lowered in the same manner as the operation of the mail box 18 in the compartment 12 and shaft 15. In other words, each shaft constitutes a separate unit having a separate motor and electric circuit which is automatically controlled by the opening and closing of a door which communicates with the top portion of the shaft of such unit.

It will also be apparent that I may employ any number of tubular shafts or runways, and said shafts or runways may be mounted in the building as hereinbefore described and extend to the separate floors of the building and at predetermined points on such floors and at the front or rear end portion of the building, and in such manner that the separate apartments of a building may be provided with an independent mail elevator constituting one of the units above referred to, and while I have shown certain details of construction for carrying my invention into effect, I am not necessarily limited to these details, and various changes therein and modifications thereof may be made, within the scope of the appended claims, without departing from the spirit of my invention or sacrificing its advantages.

It will be apparent that the angular or elbow-shaped portions as well as the curved and twisted portions of the shafts 14 and 16 will be of such dimensions or enlarged to such an extent as to permit of the free passage of the mail boxes therethrough in the upward and downward movements thereof, and in Fig. 1 of the drawing I have indicated in dotted lines the position of the mail box as it passes through the elbow portions 19 of the shaft 14.

Having fully described my invention, what I claim as new and desire to secure by Letters Patent, is—

1. An apparatus of the class described comprising a tubular shaft, a mail receiving compartment at the bottom of said shaft, a door at the top portion of said shaft, a mail

- box, means involving an electric motor for mechanically moving said mail box upwardly and downwardly through said shaft to bring said mail box in juxtaposition to said door and to said mail receiving compartment, and means whereby the opening and closing of said door will automatically control the circuit to said motor to control the operation of said mechanical means.
- 10 2. An apparatus of the class described comprising a tubular shaft, a mail receiving compartment at the bottom of said shaft, a door at the top portion of said shaft, a mail box, means involving an electric motor for mechanically moving said mail box upwardly and downwardly through said shaft to bring said mail box in juxtaposition to said door and to said mail receiving compartment, means whereby the opening and closing of said door will automatically control the circuit to said motor to control the operation of said mechanical means, and means for stopping the upward and downward movements of said mail box.
- 15 3. An apparatus of the class described comprising a tubular shaft, a mail receiving compartment at the bottom of said shaft, a door at the top portion of said shaft, a mail box, means involving an electric motor for mechanically moving said mail box upwardly and downwardly through said shaft to bring said mail box in juxtaposition to said door and to said mail receiving compartment, means whereby the opening and closing of said door will automatically control the circuit to said motor to control the operation of said mechanical means, and means for breaking the circuit to said motor to limit the upward and downward movement of said mail box.
- 20 4. An apparatus of the class described comprising a shaft, a mail box adapted to pass upwardly and downwardly through said shaft and normally located at the lower end portion thereof, means whereby mail may be placed in said box when in its normal position, a door at the upper end portion of said shaft and adapted to communicate with said mail box when in its raised position, means for mechanically raising said mail box in said shaft, means for mechanically lowering said mail box, an electric motor for operating both of said mechanical means, and means for automatically controlling the circuit to said motor to control the movement of said mail box.
- 25 5. An apparatus of the class described comprising a shaft, a mail box adapted to pass upwardly and downwardly through said shaft and normally located at the lower end portion thereof, means whereby mail may be placed in said box when in its normal position, a door at the upper end portion of said shaft and adapted to communicate with said mail box when in its raised position, means for mechanically raising and lowering said mail box in said shaft, an electric motor for operating said means, means for automatically controlling the circuit to said motor to control the movement of said mail box, two pulleys mounted at the upper end of said shaft, cables mounted on said pulleys and the free ends of which are connected with the top and bottom of said mail box, means for rotating said pulleys in opposite directions whereby said mail box may be mechanically raised and lowered in said shaft, means whereby the opening and closing of said door will control the circuit to said motor to automatically raise and lower the mail

cate with said mail box when in its raised position, means for mechanically raising and lowering said mail box in said shaft, an electric motor for operating said means, means for automatically controlling the circuit to said motor to control the movement of said mail box, two pulleys mounted at the upper end of said shaft, cables mounted on said pulleys and the free ends of which are connected with the top and bottom of said mail box, and means for rotating said pulleys in opposite directions whereby said mail box may be mechanically raised and lowered in said shaft.

6. An apparatus of the class described comprising a shaft, a mail box adapted to pass upwardly and downwardly through said shaft and normally located at the lower end portion thereof, means whereby mail may be placed in said box when in its normal position, a door at the upper end portion of said shaft and adapted to communicate with said mail box when in its raised position, means for mechanically raising and lowering said mail box in said shaft, an electric motor for operating said means, means for automatically controlling the circuit to said motor to control the movement of said mail box, two pulleys mounted at the upper end of said shaft, cables mounted on said pulleys and the free ends of which are connected with the top and bottom of said mail box, means for rotating said pulleys in opposite directions whereby said mail box may be mechanically raised and lowered in said shaft, and means whereby the opening and closing of said door will control the circuit to said motor to automatically raise and lower the mail box in said shaft.

7. An apparatus of the class described comprising a shaft, a mail box adapted to pass upwardly and downwardly through said shaft and normally located at the lower end portion thereof, means whereby mail may be placed in said box when in its normal position, a door at the upper end portion of said shaft and adapted to communicate with said mail box when in its raised position, means for mechanically raising and lowering said mail box in said shaft, an electric motor for operating said means, means for automatically controlling the circuit to said motor to control the movement of said mail box, two pulleys mounted at the upper end of said shaft, cables mounted on said pulleys and the free ends of which are connected with the top and bottom of said mail box, means for rotating said pulleys in opposite directions whereby said mail box may be mechanically raised and lowered in said shaft, means whereby the opening and closing of said door will control the circuit to said motor to automatically raise and lower the mail

box in said shaft, make and break devices in the circuit to said motor, and means for actuating said devices at the limit of the upward and downward movement of said mail box to break the circuit to said motor.

8. An apparatus of the class described comprising a shaft, a mail box adapted to pass upwardly and downwardly through said shaft and normally located at the lower end portion thereof, means whereby mail may be placed in said box when in its normal position, a door at the upper end portion of said shaft and adapted to communicate with said mail box when in its raised position, means for mechanically raising and lowering said mail box in said shaft, an electric motor for operating said means, means for automatically controlling the circuit to said motor to control the movement of said mail box, two pulleys mounted at the upper end of said shaft, cables mounted on said pulleys and the free ends of which are connected with the top and bottom of said mail box, means for rotating said pulleys in opposite directions whereby said mail box may be mechanically raised and lowered in said shaft, means whereby the opening and closing of said door will control the circuit to said motor to automatically raise and lower the mail box in said shaft, make and break devices in the circuit to said motor, means for actuating said devices at the limit of the upward and downward movement of said mail box to break the circuit to said motor, and tensional means for taking up the slack in said cable.

9. In an apparatus of the class described, a plurality of mail elevator shafts the lower end portions of which are located in juxtaposition and at a predetermined point in a building and the upper end portions of which extend to predetermined points, mail boxes mounted in and adapted to be moved upwardly and downwardly through said shafts, mechanical means in each of said shafts for pulling said mail boxes upwardly and downwardly in said shaft, electrical motors for operating said mechanical means, doors at the top portions of said shafts, means whereby the opening and closing of

said doors will automatically control the circuit to said motors to regulate the operation thereof, and make and break devices in the circuits to said motors for breaking said circuits to limit the upward and downward movement of said mail boxes in said shafts.

10. A mail elevator apparatus of the class described comprising a shaft, a mail box movable vertically in said shaft, pulleys mounted at the top portion of said shaft, cables on said pulleys and connected with said mail box, and means involving an electric motor for rotating said pulleys in opposite directions through tensional devices to raise and lower the mail box in said shaft.

11. A mail elevator apparatus of the class described comprising a shaft, a mail box movable vertically in said shaft, pulleys mounted at the top portion of said shaft, cables on said pulleys and connected with said mail box, means involving an electric motor for rotating said pulleys in opposite directions through tensional devices to raise and lower the mail box in said shaft, and means in the circuit to said motor for automatically controlling the movement of said mail box in said shaft.

12. A mail elevator apparatus of the class described comprising a shaft, a mail box movable vertically in said shaft, pulleys mounted at the top portion of said shaft, cables on said pulleys and connected with said mail box, means involving an electric motor for rotating said pulleys in opposite directions through tensional devices to raise and lower the mail box in said shaft, means in the circuit to said motor for automatically controlling the movement of said mail box in said shaft, and means for automatically stopping the upward and downward movements of said mail box.

In testimony that I claim the foregoing as my invention I have signed my name in presence of the subscribing witnesses this 22nd day of May, 1920.

DANIEL A. DORAN,
